UNITED STATES PATENT OFFICE.

CARL W. WEISS, OF BROOKLYN, NEW YORK.

AIR-DISTRIBUTER FOR INTERNAL-COMBUSTION ENGINES.

1,220,805.

Specification of Letters Patent. Patented Mar. 27, 1917.

Application filed June 29, 1916. Serial No. 106,580.

To all whom it may concern:

Be it known that I, CARL W. WEISS, a citizen of the United States, residing in the borough of Brooklyn of the city of New York, in the State of New York, have invented certain new and useful Improvements in Air-Distributors for Internal-Combustion Engines, of which the following is a specification, reference being had to the accompanying drawings, forming a part hereof.

This invention relates to an air distributor for use in starting and reversing multiple cylinder internal combustion engines. It has for its general object a distributor which shall be simple in construction, easy of manipulation and certain in action for the purpose of introducing air into the appropriate cylinder for the starting or reversing of an internal combustion engine. As will be understood, it is necessary that a device of the character described shall permit the air to be led to the proper cylinder upon manual manipulation for the starting or reversing operation and shall insure the subsequent timely admission of air to each of the remaining cylinders in proper phase relation to the cycle of movements of the pistons in the respective cylinders, after such initial manual setting. In accordance with the invention the distributor embodies a valve which shall be operable manually for admitting air into the proper cylinder for starting or reversing and a rotary distributing sleeve operatively connected to the crank shaft of the motor. These two controlling elements for the admission of air, one for manual operation and the other for mechanical operation by the motor, are both simple in construction and so related to one another and to the supporting housing as to be readily accessible for inspection and repair, invariable in operation and, in the case of the hand valve, easy of manipulation. These and other advantages of the improved construction will be described in greater detail with reference to the accompanying drawings, in which—

Figure 1 is a view in side elevation of a four-cylinder internal combustion engine provided with the improved distributor, parts of the wall of the crank case being broken away to illustrate the relative positions of the crank arms.

Fig. 2 is a detail view, on a somewhat larger scale, taken in horizontal section

through the distributor along the plane indicated by the line 2—2 of Fig. 3.

Fig. 3 is a view in vertical section through the improved distributor taken on the plane indicated by the line 3—3 of Fig. 2 and looking in the direction of the arrows.

The improved distributor *a* has been shown as applied to a four-cylinder internal combustion marine engine *b* in which the cylinders have been numbered 1, 2, 3, 4, for the sake of convenience, but it will be evident as the description proceeds that the usefulness of this distributor is in nowise dependent upon the number of cylinders of the motor to which it is applied nor to the character of the motor. For the purposes of this description, it will make for clarity to number the ports in the elements of the distributor to correspond to the cylinders which such ports control and to number the air conduits *c* with corresponding numerals so that the course of the air from the interior of the distributor *a* to each one of the cylinders may be readily traced from the drawings. The distributor proper, in the illustrated embodiment, includes an outer cylindrical casing *A* which may be supported conveniently on the engine, as by a suitable bracket *A'* and this casing *A* has formed in its inner wall cored segmental chambers *A*² with which communicate respectively the air pipes *c*, numbered 1, 2, 3, 4, according to the cylinder with which each communicates. The segmental chambers *A*² may be of any approved form and size, preferably extending about the inner wall of the casing *A* through an angle of about 180° and are disposed directly above one another so that the pipes *c* are alined. The cylindrical casing *A* is open-ended to receive a cylindrical sleeve *d* which extends downward into the casing *A* and is supported in fixed position with relation to the casing by means of an annular flange *d'* through which may pass fastening screws *d*². The fixed sleeve *d* has formed in its wall two sets of ports *d*³, *d*⁴, set at an angle of 90° apart, respectively, and in each of these sets there is a port opposite each of the segmental chambers *A*². The depending sleeve *d* is shouldered, as at *d*⁵, to provide an annular space between the inner wall of the casing *A* and the outer wall of the sleeve, in which space is mounted an open-ended tubular distributing sleeve *e* which encircles the depending sleeve *d* and lies in snug engagement with said sleeve and with the inner

wall of the casing A. The edge of this distributing sleeve e bears against the shoulder d⁵ and makes snug engagement therewith while the closed end of the sleeve is grooved, 5 as at e', to receive loosely, but in driving engagement therewith, a tongue f of a stub shaft f', which is geared to the crank shaft b' through bevel gears f², b². The distributing sleeve e has formed therein four ports 10 g, which are set at 90° apart around the periphery of the sleeve and are disposed opposite the segmental chambers A², respectively. These ports g are indicated further by the numerals 1, 2, 3, 4, corresponding to 15 the cylinders 1, 2, 3, 4, which the ports control.

In the depending sleeve d is disposed a tubular valve h, the stem h' of which extends upward through the cap formed by 20 the end wall of the sleeve d and has secured thereto an operating handle h² by means of which the valve may be operated for the purpose of starting, reversing or stopping the motor in a manner which will be described. The valve h has formed therein 25 four ports h³ which are alined with relation to one another and are disposed opposite the four segmental chambers A², respectively. This valve fits snugly within the depending 30 sleeve d and is so set with relation thereto that the ports h³ therein normally rest midway between the sets of ports d³, d⁴ in said sleeve, but may be carried into registry with either of these sets of ports by operation in 35 one direction or the other under the influence of the hand lever h², for the purpose of starting or reversing the engine in the manner to be pointed out in connection with the operation of the distributor.

40 Adjacent the lower end of the frame A is formed an annular cored chamber A³ with which communicates the main supply pipe i for compressed air, the air being admitted from this chamber A³ into the interior of the 45 tubular valve h through a series of openings e² formed in the lower end of the distributing sleeve e and in line with said chamber.

During normal operation of the motor, by 50 its usual fuel, the hand lever h² will be positioned mid-way between suitable bosses d⁵ formed on the outer face of the flange d' for the purpose of limiting the oscillating movement of the handle in one direction or the other. With the handle h² in this median position the valve h will be placed in the position shown in Fig. 2 in which the ports h³ thereof are blanked by the wall of the sleeve d lying between the sets of ports d³, d⁴. At this time, it is evident that no 55 air can pass from the interior of the distributor to any of the cylinders. If it is desired to start the engine by compressed air, assuming it to be at rest, the hand lever h² may be manipulated to bring the ports h³ into registry with the ports d⁴ of one of

the sets in the depending sleeve d, whereupon air will be admitted from the interior of the valve to that segmental chamber A² which has a port g of the distributing sleeve e in line with one of the ports h³ and the registering port d⁴ in the fixed sleeve. As shown in Fig. 2, the port g in the distributing sleeve e indicated by the numeral 3, laps over one of the ports d³ in the fixed sleeve d, so that if the hand valve h were oscillated 70 to bring one of the ports h³ into line with said port d³ and the distributor port g (numbered 3) air would be admitted from the interior of the valve h to that air pipe c which is numbered 3 in Fig. 1 and is in line with the chamber A² controlled by the port g (numbered 3). Fig. 1 indicates plainly that the piston k in cylinder 3 is in such position that air admitted through the pipe c (numbered 3) into the cylinder would 75 serve to force the piston downward and commence rotation of the crank shaft in the desired direction. Such rotation would obviously cause rotation of the distributing sleeve e through the driving gears b², f², in a clockwise direction, as viewed in Fig. 2, and bring the next port g (numbered 1) in line with the registering ports h³, d³, to admit air through the air pipe 1 into cylinder 1 and thereby give an impulse to the piston 80 therein and thereby continue rotation of the crank shaft. Subsequently, the other ports (numbered 4 and 2) would be brought successively into registry with the registering ports h³, d³ and admit air to the respective 85 cylinders 4, 2, for the purpose of imparting power impulses thereto. With the engine operating in the manner described, the usual fuel charge is admitted through the usual 90 devices provided therefor (not illustrated) and operation continued under the power of such fuel, whereupon the hand lever h² may be moved to its median position and the ports h³ in the valve h blanked, as heretofore 95 described, thereby cutting off the air supply. When the engine is to be reversed, the hand lever h is moved to a position against the other abutment d⁵ whereupon the ports h³ will be moved into registry with the other 100 ports d⁴ in the fixed sleeve d. This operation will find the ports h³, d⁴ in registry with the port g (numbered 4) in the distributor sleeve e, whereupon air will be admitted to the cylinder 4 through the appropriate pipe 4 communicating with said port 105 g (numbered 4). Referring again to Fig. 1, it will be seen that the piston k in cylinder numbered 4 is in such position that air admitted thereto will serve to rotate the crank shaft in a direction counter to the direction in which it was rotated under the impulse given by the piston k in the other cylinder 3, that is to say, the crank shaft 110 will be rotated in a reverse direction. Rotation of the distributor sleeve e will now be 115

120 125 130

in a counter-clockwise direction, so that the ports 1, 3 and 2 therein will be brought successively into registry with the ports h^3 , d^4 in the order named and air will be admitted to the respective cylinders in that order. The effect is to continue rotation of the crank shaft in the reverse direction named. In reversing the engine, the air will not be admitted until after the fuel supply has been fully cut off and immediately upon the reversal under the influence of the air in the manner described, the fuel will again be admitted to the cylinders for the continuous operation of the engine in the normal manner.

It is to be understood that the several ports in the elements of the distributor will preferably be of such dimensions and so arranged with relation to one another that during the starting and reversing operations air will never be cut off from all of the cylinders at any one time. In other words, the ports will have a slight lap so that each succeeding port will open to admit air to its cylinder just before the preceding port has closed to cut off air from its cylinder.

A structural detail of importance resides in the formation of an annular shoulder A^4 at the bottom of the casing A to receive a flanged bushing l through which passes the stub shaft f' for the driving of the distributing sleeve e . This stub shaft f' itself is flanged, as at f^3 , and this flange may rest on the flange of the bushing so that the annular shoulder A^4 in fact supports the stub shaft f' . Since the distributing sleeve e rests on the tongue f of the stub shaft f' , so as to effect a loose driving connection between the tongue and the groove e' , it may be said that the annular shoulder A^4 of the casing A supports this distributing sleeve as well and that floating engagement between the distributing sleeve and its driving shaft which is desirable under the conditions of use to which the distributor is placed, is secured.

By the construction described, it will be evident that the stopping, starting and reversing of the engine may be effected by compressed air through a very simple manipulation of the hand lever h^2 and that the danger of accident through careless manipulation is minimized and certainty of operation insured. Appropriate legends "Stop," "Start," "Reverse" may be placed on the cap of the sleeve d directly under the corresponding positions of the handle h^2 as convenient indications. Again, the positive mechanical connection between the distributing sleeve e and the crank shaft f' insures the invariable operation and proper timing of this sleeve and the invariable admission of air to the several cylinders in proper sequence and time relation to the cycle of movements of the respective pistons.

Changes may be made in the relative ar-

rangement of the elements of the distributor and their form and dimensions without departing from the spirit of the invention provided the advantages described herein are realized by means which are substantial equivalents to those recited in the appended claims.

I claim as my invention:

1. An air distributor for multiple cylinder internal combustion engines, comprising a casing having chambers in communication with the respective cylinders, a rotary distributor sleeve in the casing having ports therein corresponding to the respective chambers, operative driving connections between the sleeve and the crank shaft, a tubular valve within the casing provided with ports corresponding in number to the first named ports, the ports in one of said elements being aligned with one another and the ports in the other of said elements being staggered with relation to one another.

2. An air distributor for multiple cylinder internal combustion engines, comprising a casing having chambers in communication with the respective cylinders, a rotary distributor sleeve in the casing having ports therein corresponding to the respective chambers but staggered with relation to each other, operative driving connections between the sleeve and the crank shaft, a tubular valve within the casing provided with ports corresponding in number and relative disposition to the chambers, and a source of compressed air for the casing.

3. An air distributor for multiple cylinder internal combustion engines, comprising a casing having chambers in communication with the respective cylinders, a fixed sleeve within the casing having ports aligned with the respective chambers, an oscillating tubular hand valve within the casing provided with ports corresponding in number and relative disposition to the ports in said sleeve, and a source of compressed air for the casing.

4. An air distributor for multiple cylinder internal combustion engines, comprising a casing having chambers in communication with the respective cylinders, a fixed sleeve having ports aligned with the respective chambers, a rotary distributor sleeve in the casing, operative driving connections between the distributor sleeve and the crank shaft, an oscillating tubular hand valve within the casing provided with ports corresponding in number and relative disposition to the ports in said fixed sleeve, and a source of compressed air for the casing.

5. An air distributor for multiple cylinder internal combustion engines, comprising a casing having chambers in communication with the respective cylinders, a rotary distributor sleeve in the casing, ports for each of the chambers displaced with respect to

one another, operative driving connections between the sleeve and the crank shaft, and a fixed sleeve within the casing having two sets of alined ports disposed, respectively, 5 opposite the said chambers, said sets of ports being displaced with relation to each other an angular distance equal to the displacement of said ports in the distributer.

6. An air distributer for multiple cylinder 10 internal combustion engines, comprising a casing having chambers in communication with the respective cylinders, a fixed sleeve in said casing having two sets of alined ports in alinement with the respective chambers, a tubular oscillating hand valve having a single set of alined ports disposed opposite the ports in the sleeve, respectively, and a rotary distributing sleeve having a 15 port for each chamber, the ports in the distributing sleeve being displaced with relation to each other an angular distance equal to the displacement of the said two sets of ports in the fixed sleeve.

7. An air distributer for multiple cylinder 20 internal combustion engines, comprising a vertically disposed tubular casing having

cored segmental chambers on its inner wall, disposed one above another and corresponding in number to the number of cylinders, a cover plate for the casing on which is 30 formed a depending sleeve, a rotary distributor sleeve mounted in the casing between said fixed sleeve and the wall of the casing, a tubular hand valve carried within the fixed sleeve, a cored chamber in the wall of the 35 casing to receive compressed air, openings in the distributor sleeve to admit said compressed air from said chamber into the interior of the hand valve, a single set of alined ports disposed opposite the chambers, respectively, two sets of alined ports in the fixed sleeve disposed opposite the chambers and the ports in the hand valve, and a port in the distributor sleeve for each chamber, the last named ports being displaced with relation to 40 one another a distance at least equal to the displacement of the two sets of ports in said fixed sleeve.

This specification signed this 27th day of June A. D. 1916.

CARL W. WEISS.
